FIG. 2.

FIG. 3.

FIG. 1.

INVENTOR
Charles Corliss McBride.

BY
Francis C. Huebner,
ATTORNEY

UNITED STATES PATENT OFFICE.

CHARLES CORLISS McBRIDE, OF SANGER, CALIFORNIA.

AMALGAMATING CELL.

Application filed October 22, 1921. Serial No. 509,665.

To all whom it may concern:

Be it known that I, CHARLES CORLISS McBRIDE, a citizen of the United States, and resident of Sanger, in the county of Fresno and the State of California, have invented a new and useful Improvement in Amalgamating Cells, of which the following is a specification.

My invention relates to an electric amalgamator for separating metals from sand and ore pulp.

One object I have accomplished is to produce a sluice having an amalgamated bottom which will be in contact with flowing mercury subjected to a sodium chloride solution bath, and to an electric current, the sodium chloride solution being constantly sealed from direct contact with the contents of the sluice.

A further object is to improve the efficiency of the mercury by passing a current of electricity through a sodium chloride solution to the mercury, thus impregnating the mercury with metallic sodium, at the same time circulating the mercury so as to bring it into contact with ore pulp or sand containing precious metals, while said sand is being transported through the sluice by means which does not come in direct contact with the sodium chloride solution.

I accomplish these and other objects hereinafter set forth by means of the device hereinafter described and illustrated on the accompanying drawing in which Figure 1 shows a top view of the device, showing a fractional view of the sluice. Figure 2 is a sectional view of the device along the line 2—2 in Figure 1. Figure 3 is a sectional view of the device along the line 3—3 in Figure 1.

My device consists of a sluice S having a bottom constructed of an amalgamated plate C and two sides D and D¹. Sides D and D¹ project below the bottom plate C, said extensions being shown as P and P¹. A transverse section of bottom plate C is removed, and a grizzly G is attached to the under surface of plate C so that the grizzly will cover the opening. On each side of the sluice box and adjacent to the grizzly are boxes or compartments B and B¹ the interiors of which are connected by a duct K extending from an opening V in the bottom of one box to an opening V¹ in the bottom of the

other box. Duct K passes under the sluice and the plate C forms the top thereof. This duct is approximately the width of the grizzly and passes directly thereunder. A lineal sectional view of duct K as shown in Figure 2 discloses the shape of the bottom to be two channels H and H¹ located directly under the extensions P and P¹, and in line therewith, said channels being connected with a member H². The bottom of the duct is constructed water tight.

A tube T also connects compartments B and B¹ extending from openings T¹ and T² in the bottoms of said compartments, which openings are a spaced distance from the duct openings V and V¹. E is an electrical heater attached to tube T and adapted to heat the mercury in tube T at a point adjacent to the opening T². The duct K and the bottom of compartments B and B¹ are filled with mercury to the broken line M which is approximately at the top of the grizzly and the compartments B and B¹ are then filled with sea water, or with a solution containing sodium chloride approximately to the broken line N. It is noted that line N is arbitrarily formed, one feature of my invention consisting in having sea water or a solution containing sodium chloride within the compartments on the top of the mercury without regard to the exact amount therein. I have placed anodes A and A¹ within boxes B and B¹ and have properly insulated them from the walls of the boxes. These anodes should be located within the boxes so they will be immersed in the sea water or sodium chloride solution and so they are not in contact with the mercury therein. A cathode L is inserted in the bottom H² preferably under the grizzly so that it is immersed in the mercury, and insulated from the box. The anodes A and A¹ and the cathode L are attached to a source of electrical energy, preferably to a direct current.

In operating this device when the mercury and sea water or sodium chloride solution are within the duct and boxes as hereinbefore described and a direct current of electricity is introduced through anodes A and A¹ through the sodium chloride solution to the mercury cathode, deposits of metallic sodium are gathered by the mercury

cathode from the sea water, which evolves chlorine and hydrogen gases which function to clean the mercury and increase its activity. When the mercury in tube T is warmed at 5 a point on the tube adjacent to the outlet T², the thermo-syphon action causes a circulation of the mercury through duct K and tube T, thus constantly bringing mercury which has been in direct contact with the sodium 10 chloride solution across grizzly G and in contact with the amalgamated plate C and the ore pulp or sand which may be passing through the sluice. By this process metals which would be lost under other methods of 15 extracting precious metals from sand and pulp are amalgamated on the upper surface of amalgamated plate C. By this means the benefit of having the mercury come into contact with the sodium chloride solution is 20 had without wasting it through the sluice.

In connection with the specification hereinbefore set forth it is noted that as the extensions P and P¹ depend downward into the mercury an effective seal is produced 25 which prevents the sodium chloride solution from passing into the duct K, and through the grizzly into the sluice. This object could be accomplished if the sides D and D¹ were flush with the bottom C and the mercury 30 level was kept constantly level with the bottom of plate C but in practice it has proven better to have the water more effectively sealed from the portion of the duct under plate C by the means described. The 35 formation of channels H¹ and H² and the elevation of bottom H² is for the purpose of economizing in the amount of mercury necessary to operate the device.

It is further noted that in applying the 40 principle of my invention it is not necessary to have two compartments for the sodium chloride solution, but one can be adapted for the purpose by connecting the ends of duct K and tube T opposite to the compartment. The heater E is intended solely to produce a circulation of the mercury. This 45 can be accomplished by numerous other means, such as a pump or a screw adapted to keep the mercury flowing.

50 Having described my invention I claim as new and ask for Letters Patent:

1. In an amalgamator the combination of a sluice having an amalgamated plate with an opening therethrough forming a 55 part of the bottom, and a grizzly attached to the under surface of the bottom and covering the opening, a container formed independent of the sluice having a duct leading from the bottom of the container and 60 extending under the bottom of the sluice, the duct having an opening in its top registering with the opening in the amalgamated plate, a return lead from the duct at a point beyond the amalgamated plate to the 65 container, mercury within the duct and cov-

ering the bottom of container to the level of the amalgamated plate, a solution containing sodium chloride within the container above the mercury, electric leads from a source of electrical energy to the 70 mercury and to the solution containing sodium chloride, and means for keeping the mercury in circulation in the duct, substantially as described.

2. In an amalgamator the combination of 75 a sluice having an amalgamated plate for a bottom, and the sides of which extend above and below said bottom, said plate having an opening therethrough into which a grizzly is inserted, a container independent of the sluice having a duct leading from the bottom thereof under the grizzly and amalgamated plate, said amalgamated plate forming the upper wall of the duct and the depending portions of the sides of 80 the sluice depending within the duct, a return lead from the duct beyond the grizzly to the container, mercury within the duct and covering the bottom of container to the bottom of the amalgamated plate, a solution containing sodium chloride within the container above the mercury, electric leads from a source of electrical energy to the 85 mercury and to the solution containing sodium chloride, and means for keeping the mercury in circulation in the duct, substantially as described.

3. In an amalgamator, the combination of a sluice having an amalgamated plate in the bottom, the sides of the sluice extending above and below said amalgamated plate, said plate having an opening therethrough which is covered by a grizzly attached to the under side of the plate, a container constructed on the outside wall of the 100 sides of the sluice, a duct connecting the interior of the containers, and extending under and around the sides of the sluice and under the grizzly, said grizzly forming a portion of the duct, and the lower portions 105 of the sides of the sluice depending within the duct, a lead connecting the interior of the containers at points a spaced distance from the terminations of the ducts, mercury within the duct and covering the bottom of 110 container to the bottom of the amalgamated plate, a solution containing sodium chloride within the container above the mercury, electric leads from a source of electrical 115 energy to the mercury and to the solution containing sodium chloride, and means for keeping the mercury in circulation in the duct, substantially as described.

4. In an amalgamator the combination of 120 a sluice having an amalgamated plate with an opening therethrough forming a part of the bottom, and a grizzly attached to the under surface of the bottom and covering the opening, a container having a duct leading from the bottom of the container and 125

extending under the bottom of the sluice, the duct having an opening in its top registering with the opening in the amalgamated plate, a return lead from the duct at a point 5 beyond the amalgamated plate to the container, mercury within the duct and covering the bottom of container to the bottom of the amalgamated plate, a solution containing sodium chloride within the container above the mercury, electric leads 10 from a source of electrical energy to the mercury and to the solution containing sodium chloride, substantially as described.

CHARLES CORLISS McBRIDE.
